PROCESS OF MAKING SOAP

Henry Randel Dickinson, Grand Rapids, Mich.,
and Henry H. Moreton, Santa Monica, Calif.

Application July 25, 1935, Serial No. 33,149

5 Claims. (Cl. 260—413)

This invention is a process of making soap, and more particularly relates to the manufacture of soap flakes or powder.

One of the objects of the invention is to effect the manufacture of soap without employing the usual soap-makers' vats or tanks of the type commonly employed in soap manufacture. A further object is to provide a process by means of which soap may be manufactured by directly combining the fats and chemicals used, without the use of any intermediate apparatus involving a boiling operation. A further object of the invention is to effect manufacture of soap in any form from liquid soaps to solid soaps.

15 The invention will be hereinafter fully set forth and particularly pointed out in the claims.

In the accompanying drawing:—

Figure 1 is a diagrammatic view illustrating one form of apparatus designed for the practice 20 of the invention. Figure 2 is a detail longitudinal sectional view of the mixing nozzle. Figure 3 is a similar view illustrating a modification.

Referring to the drawing, 10 designates a supply tank for the fats, oils, etc., either heated 25 or cold, which is connected with the inner branch 11 of a nozzle 12, in such manner as to feed to the latter by gravity. If, however, an increased pressure is desired, a pump 13 may be provided 30 in the line between the service tank and the nozzle. Communicating with the outer conduit 14 of the nozzle 12 is another service tank 15 adapted to contain a lye mixture, either heated 35 or cold and which may be supplied to the nozzle by gravity, or under pressure by pump 16, if desired. By the term "lye mixture" or "lye solution" used in the specification and claims is means any of the well known sodium, potassium or other similar alkaline solutions that have been 40 in common use in the soap making art for many years. The knowledge of the art in this particular is so well established that it is deemed unnecessary to specify such solutions with greater particularity.

45 A source of steam or other heated fluid, indicated at 17, is also employed, the same discharging into an injector or mixer of any desired construction, indicated at 18, and located in the pipe line between the service tank 15 and the nozzle.

50 The nozzle 12 projects into the upper end of a collecting chamber 20, which is provided with a discharge pipe 21 at its lower end. Said discharge pipe is connected by a pipe 22 to a collector 23, preferably of the cyclone type, having

a discharge pipe 24 at its lower end, an exhausting device 25 being connected to the top of the separator. Pipes 22 and 24 are controlled by valves 22^a and 24^a respectively. An air inlet opening 26 is provided in chamber 20 adjacent to 5 nozzle 12.

In operation, the flowing stream consisting of a mixture of lye and steam, or other heated fluid is caused to travel to the nozzle 12 and to be discharged into the collecting chamber 20. The 10 pressure of the flowing stream of lye mixture draws the oils and fats from the tank 10 and induces a stream thereof to also flow to said nozzle, and to be discharged into said collecting chamber. As they reach the nozzle the two 15 streams are commingled, and atomized under the pressure of the inducing stream and by reason of their discharge into the tank 20, the size of which is sufficient to provide for a very substantial reduction of pressure, as the mixture is discharged thereinto. In other words, the mixing 20 of the fat constituents with the heated lye solution is effected at the nozzle 12, at the approximate instant of the discharge of the mixture from the nozzle into the chamber 20. Thus, the 25 mixing and discharging stages are approximately simultaneous. The induced flow of the stream of fat constituents by the flow of the stream of lye solution effects proportionate mixing of the materials of the two streams at the instant of 30 discharge, resulting in complete saponification. One of the functions of the nozzle is that by means of the induced vacuum created thereby, a supply of air is added to the atomized mixture, if desired, through the air inlet 26. The result 35 of the foregoing operation is an immediate saponification of the fats plus the drying of the product produced, provided that drying is desired.

After the soap has been produced by the atomized step above referred to, it is collected in powder form within the chamber 20, and may be withdrawn from the latter through the discharge pipe 21. If desired, however, the collector 23 may be placed into communication with the tank 45 20 through pipes 21 and 22, and thereby a more complete separation of the powdered soap may be accomplished, the moisture carried by the air being removed from the collector 20 by means of the exhausting device 25. In the event that the 50 soap is required to be in liquid form, a greater amount of steam is used at the nozzle 12, and/or less air is introduced through inlet 26, and in this case the liquid soap will be collected in the tank 20, and may be removed in any desired 55

manner, as for instance through the discharge pipe 21. When soap in solid form is desired, a powder is made containing a relatively high water content, and the powder is then pressed 5 into cakes in a standard soap-cake machine.

While it is preferred to employ a nozzle 12 having two orifices, one of which receives a mixture of lye and heating medium such as steam, the mixer 18 may be omitted and the steam may 10 be introduced directly to the nozzle through a third orifice, as shown in Fig. 3.

By regulating the quantities of air and/or steam introduced into the tank 20, the moisture content of the soap can be varied at will.

15 The advantages of the invention will be clearly apparent to those skilled in the art to which it belongs. For instance, it is readily obvious that an improved process of making soap is provided, whereby a more complete saponification is made 20 possible, due to the extremely fine intermingling and emulsifying of the chemicals and the fats. An important advantage is that the saponification is made by bringing the streams of oil or 25 fat and the chemicals into intimate relation in such manner that the soap is instantly formed, thereby rendering it unnecessary to employ vats, tanks or other intermediate boiling apparatus.

Having thus explained the nature of the invention and described an operative manner of 30 constructing and using the same, although without attempting to set forth all of the forms in which it may be made, or all of the forms of its use, what is claimed is:—

1. A process of making soap comprising creating 35 a positively flowing stream of heated lye solution, causing the flowing stream of heated lye solution to induce the flow of a liquid containing fat constituents, and effecting saponification by causing the two flowing streams to mix and then 40 to be atomized by being discharged into space through an atomizing orifice, the mixing stage being effected back of but closely adjacent to said orifice.

2. A process of making soap comprising heating 45 a liquid lye solution by mixing the same with steam and creating a positively flowing stream of the mixture by the pressure of said steam, causing the flowing stream of steam and lye solution to induce the flow of a liquid containing fat

constituents, and effecting saponification by causing the two flowing streams to mix and then to be atomized by being discharged into space through an atomizing orifice, the mixing stage being effected immediately back of but closely adjacent to said orifice.

3. A process of making soap comprising heating a liquid lye solution by intermixing the same with steam, and creating a positively flowing stream of the mixture by the pressure of the 10 steam, causing the flowing stream of heated lye solution to induce the flow of a liquid containing fat constituents, and effecting saponification by causing the two flowing streams to mix and then to be atomized by being discharged into space 15 through an atomizing orifice, the mixing stage being effected immediately back of but closely adjacent to said orifice and controlling the density of the saponified constituents by varying the proportions of steam introduced into said lye 20 mixture.

4. A process of making soap comprising creating a positively flowing stream of heated lye solution, causing the flowing stream of heated lye solution to induce the flow of a liquid containing 25 fat constituents, effecting saponification by causing the two flowing streams to mix and then to be atomized by being discharged into a closed chamber through an atomizing orifice, the mixing stage being effected immediately back of but 30 closely adjacent to said orifice and introducing air into said chamber in such manner as to control the moisture content.

5. A process of making soap comprising creating a positively flowing stream of heated lye 35 solution, causing the flowing stream of heated lye solution to induce the flow of a liquid containing fat constituents, effecting saponification by causing the two flowing streams to mix and then to be atomized by being discharged into a closed 40 chamber through an atomizing orifice, the mixing stage being effected immediately back of but closely adjacent to said orifice introducing air into said chamber in such manner as to control the moisture content, partially dehydrating 45 the saponified material, and then compressing the dehydrated mass into solid increments.
